ATTORNEY:

UNITED STATES PATENT OFFICE

BERT O. TILDEN, OF TRENTON, NEW JERSEY, ASSIGNOR TO B. O. T. MFG. CO., OF TRENTON, NEW JERSEY, A CORPORATION OF NEW JERSEY

FLUSH VALVE

Application filed August 27, 1930. Serial No. 478,108.

This invention relates to flush valves to be operated in connection with water closets, and the like, and has for its object to provide novel construction and arrangement of the flushing mechanism, wherein the flush valve, which is preferably annular, is supported entirely by, and is movable with, a reciprocable over-flow pipe, and wherein the valve float is also supported by the said over-flow pipe, all of said parts being arranged concentric or having a common axis, and being guided by a float cylinder, which is disposed concentric to the over-flow pipe, the valve body, and the outlet or discharge spud. A further object is to provide an over-flow pipe, which is movable and straight, instead of being stationary and formed with the usual right angle offset to carry the waste water from an eccentrically disposed pipe to the waste opening. By this novel disposition and arrangement of the over-flow pipe, the disposal of the over-flow or waste water is more positive, free and rapid and obviates all danger of the flush tank over-flowing, in case the ball-float becomes accidentally detached from the ball-cock, and besides, the arrangement whereby the over-flow discharges directly through the valve when the latter is closed, renders the operation entirely noiseless. And a further object is to provide a combined flush valve, valve float, float chamber and over-flow pipe, that may be assembled at the factory and shipped and installed as one part, and which is extremely simple, strong and durable. The present flush valve, which may comprise a relatively thick, leather or rubber disc, and requires no particular adjustment, and but infrequent renewal, is designed to supplant the common, frail, hollow, rubber, spherical valves, which are prone to leakage, and to become shattered and water-logged, and in a short time rendered useless.

I attain these objects by the means set forth in the detailed description which follows, and as illustrated by the accompanying drawings, in which—

Figure 1 is a top plan view of the flush tank with the cover removed. Fig. 2 is a

central vertical, longitudinal section, taken substantially on line 2—2 of Fig. 1, showing the valve and related parts in elevation, the valve being in the open position. Fig. 3 is a central transverse sectional view of the flush valve and related parts, the valve being closed. And Fig. 4 is a partial elevation and partial central vertical section of the flow pipe, the float and flush valve. In the drawings, 2 represents a china or other flush tank, whose bottom 2' is formed with a central opening 2a for flushing purposes, and an opening 2b for the in-flow of the flushing water, and 2c represents the usual cover for the tank. 3 represents the fresh water supply pipe, which is fitted with an elevated ball-cock 3', that supports a pipe 3a employed for refilling the tank, following each flushing operation. The ball-cock is controlled by the usual ball-float 4, which connects with the cock' by means of a rod 4'. 5 represents the over-flow pipe, which is disposed in axial alignment with a cage-like valve body 6, the bottom of said body comprising a threaded spud portion 6', which extends through the opening 2a, and may connect with a water closet bowl, and the like. Above the spud 6', the body 6 is formed with an integral annular portion 6a, of larger diameter than the spud, and which is adapted to over-lie, like a flange, the inner bottom surface of the tank, and α represents a nut employed to clamp the body 6 to the tank bottom. The top of the ring 6a, comprises the valve seat, as 6c, and in practice, the plane of said seat is not over a quarter of an inch above the plane of said bottom, so that at each flushing of the tank, the latter is substantially emptied. This is a very desirable feature, and will be appreciated when it is understood that in the common run of flush tanks, the flush valve seats are located one inch or more above the plane of the bottoms, which prevents a relatively large volume of the water from being dispensed for flushing purposes. Heretofore the depth of this unused water has usually been two inches or more, and this water has been prevented from flowing into the bowl, to refill the same and restore the usual trap,

because of the relatively quick closing of the older flushing valves. This necessitates the building of tanks considerably higher or broader, in order to provide the usual four gallons of flushing fluid, and renders it necessary to provide the common refill tube that conducts the refilling water from the ball-cock to the overflow pipe, which discharges it into the bowl. Spaced above the seat 6c, the body 6 is formed with another 10 annular portion or member 6d, which is supported by three or four tapered legs, as 6e, and together form a cage for the free admission of the water to the valve seat 6c, from all directions. 7 represents a cylindrical float chamber, which is normally open at its top and bottom ends. The bottom of the cylinder however, is preferably closed by a detached disc 7', which may rest upon an internal horizontal flange, as 6f, of the 15 member 6d. The disc 7' may be dispensed with and the bottom made integral with the float cylinder. The lower end of cylinder 7 and the top end of member 6d, may be correspondingly threaded for effecting a rigid 20 but detachable connection between said parts. The said parts may be provided with complementary bayonet fastening means, as shown at 7a, in Figs. 2 and 3. Within the chamber 7, is disposed loosely 25 the valve float 8, which in the instant case, is rigidly mounted concentrically upon the over-flow pipe 5. The float 8 is preferably of slightly less diameter than the bore of the cylinder 7, to enable the flushing water, 30 when its level is higher than the top of the cylinder, to gravitate past the float and fill the cylinder. The bottom 7' is formed with a central opening 7c, to receive and guide the pipe 5. This opening 7c is preferably 35 slightly larger than the pipe 5, so as to enable the water in the cylinder 7 to drain off slowly in order to retard the closing of the valve until the full volume of flushing water has passed from the bowl. In the present 40 case, the refill tube is dispensed with, and the refilling of the bowl to establish the usual trap is effected by the last few quarts of water that remain in the tank after the siphon action or effective flushing work is 45 done. 9 represents the flush valve, which is mounted rigidly on the lower end of the pipe 5 and comprises a leather or other compressible ring, as 9', which faces the seat 6c, 50 and a ring of brass or other metal, as 9a, overlies and reinforces the ring 9'. The rings 9'-9a are preferably detachably held 55 in place by a nut 9c, which may be threaded to the lower end of the overflow pipe 5. The 60 valve 9 seats by gravity, and the seating is rendered positive by the combined weight of the valve 9'-9a, over-flow pipe 5 and float 8, and the slight looseness of the float within the cylinder 7, as well as 65 the loose fit of the flow pipe, where it passes

through the bottom 7', insures the proper seating of the valve, following each flushing operation. The valve 9 may be opened by the usual manually operable handle, as 10, and lift rod 10', the free end of said rod 70 having a hook 10a, that engages a pin 5', which passes diametrically through the top end of the pipe 5, as best shown in Fig. 1. To start the flushing operation simply involves the raising of pipe 5, float 8 and the valve 9, as one part, from the position shown in Fig. 3, to that shown in Fig. 2. 75

Having thus described my invention, what I claim, is—

1. A flushing apparatus in combination with a tank having inlet and outlet openings, a valve body in register with the outlet, having a seat disposed substantially in the plane of the tank bottom, a cylinder mounted concentrically in said body, a float 80 loosely disposed in said cylinder, an annular valve, an over-flow pipe passing axially through said cylinder, said valve and said float, and being rigidly secured to both of said latter parts, adapted when raised, to enable the contents of the tank to discharge through said outlet, and means for raising said pipe, said cylinder having a closed bottom formed with an opening of greater 85 diameter than that of the pipe whereby water may drain therethrough, and said float being of less diameter than that of the cylinder, whereby water may enter the cylinder. 90

2. A flush valve for water closets, in combination with a flush tank having inlet and outlet openings, a cage-like body overlying the outlet, a cylinder rising from said cage, a valve disposed between the seat and said cylinder, an over-flow pipe passing concentrically through said cylinder, said valve being rigidly mounted on the lower end of said pipe, and a float mounted concentrically 105 on said pipe and being slidable in said cylinder, and means to lift said over-flow pipe 110 for unseating the valve to discharge the contents of the tank, said cylinder having a closed bottom formed with an opening of greater diameter than that of the pipe whereby water may drain therethrough, and said float being of less diameter than that of the cylinder, whereby water may enter the cylinder. 115

3. A flushing apparatus in combination with a flush tank and a flush valve body, 120 said body having a seat, a flush valve disposed concentrically in said body above the seat, a cylinder mounted concentrically upon said body, a float disposed concentrically and 125 slidably in said cylinder, an over-flow pipe disposed concentrically in said body and cylinder, said valve having a concentric opening to receive the lower end of said pipe, said float being rigidly mounted on said pipe and reciprocable within said cylinder, and 130

- means to raise said pipe, said valve and said float as one part, to effect the discharge of the contents of the tank, said cylinder having a closed bottom formed with an opening 5 of greater diameter than that of the pipe whereby water may drain therethrough, and said float being of less diameter than that of the cylinder, whereby water may enter the cylinder.
- 10 4. Means to flush a water closet bowl, in combination with a tank to contain the flushing water having a discharge opening in its bottom, a valve body communicating with said opening having a valve seat sub- 15 stantially in the plane of the tank bottom, an over-flow pipe disposed concentrically in said body, an annular valve mounted upon the lower end of said pipe whereby the over- 20 flow water discharges through said valve, a float cylinder rising from said body, a float rigidly mounted on the over-flow pipe and loosely fitting the cylinder, and means to lift said over-flow pipe, said float and said valve as one part, to empty said tank, said 25 cylinder having a closed bottom formed with an opening of greater diameter than that of the pipe whereby water may drain therethrough, and said float being of less diameter than that of the cylinder, whereby 30 water may enter the cylinder.
5. A flushing apparatus in combination with a tank having inlet and outlet openings, a valve body normally closing the outlet having a seat disposed substantially in 35 the plane of the tank bottom, a cylinder mounted concentrically in said body, a float slidably disposed in said cylinder, a valve between the seat and cylinder, an over-flow pipe passing axially through said cylinder, 40 said valve, and said float, and being rigidly secured to both of said latter parts, adapted when raised, to enable the contents of the tank to discharge through said outlet, and when lowered for closing the valve, to dis- 45 charge the over-flow water through the valve, and means for raising said pipe, said cylinder having a closed bottom formed with an opening of greater diameter than that of the pipe whereby water may drain there- 50 through, and said float being of less diameter than that of the cylinder, whereby water may enter the cylinder.
6. A flush tank for water closets, having in combination with the supply and exhaust 55 openings, flushing means comprising a cage-like valve body that rests upon the bottom of the tank and having a valve seat sub-stantially in the plane of said bottom, an over-flow pipe disposed concentrically in said cage, an annular flush valve secured to the lower end of said pipe and movable therewith to control the filling and emptying of the tank, a cylindrical float chamber supported by said cage concentric to said 60 over-flow pipe, a float rigidly secured to 65
- said over-flow pipe and slidable in said cylinder, and means to lift the overflow pipe, the float, and the valve, as one part, to discharge the flushing water from said tank, 70 said cylinder having a closed bottom formed with an opening of greater diameter than that of the pipe whereby water may drain therethrough, and said float being of less diameter than that of the cylinder, whereby water may enter the cylinder. 75
- In testimony whereof I affix my signature.
